UNITED STATES PATENT OFFICE.

LARS OLOF HEDBLOM, OF NEW BRUNSWICK, NEW JERSEY.

HOT-WATER HEATER AND STEAM-GENERATOR.

1,168,631.

Specification of Letters Patent. Patented Jan. 18, 1916.

Application filed April 8, 1915. Serial No. 19,968.

To all whom it may concern:

Be it known that I, LARS OLOF HEDBLOM, a subject of Gustavus V, King of Sweden, and a resident of New Brunswick, in the county of Middlesex and State of New Jersey, have invented certain new and useful Improvements in Hot-Water Heaters and Steam-Generators, of which the following is a specification.

10 My invention is an improvement in water heaters and steam generators, and especially in that class which relates to fast water heaters and consists in certain novel combinations of parts as will be hereinafter described and claimed.

One advantage of this invention is to present a very large heating surface to a small quantity of water.

Another advantage is to provide a water heater which becomes adapted to steam generation by valve readjustment.

Another advantage is to provide a heater which can be made in a variety of forms without reducing its utility.

25 Another advantage is to provide connections between separate water jackets or containers without pipes.

Another advantage is to provide a valve which shuts off all water when a certain nut is removed to permit access to the main filter of the apparatus.

Another advantage is to provide an apparatus of this class which can be entirely disassembled and inspected.

35 Another advantage is to provide an apparatus of this class that can be greatly aided in resisting pressure by utilizing securing bolts to hold the apparatus together.

Further possibilities and advantages will 40 become apparent as the specification proceeds.

With the aforesaid advantages in view, the invention comprises the improvements and combinations of parts hereinafter described in their embodiment, pointed out in the claims and illustrated in the accompanying drawings which show this set of improvements.

Figure 1 is a front view of the simplest 45 form of the invention. Fig. 2 is a vertical central cross section of the apparatus in its entirety. Fig. 3 is a top view of cylinders A or D of Fig. 2 with the super-imposed flue-block in horizontal cross section. Fig. 50 55 4 is a top view of cylinders B or E of Fig.

2 with a horizontal cross section of the super-imposed flue-block. Fig. 5 is a modification of Fig. 4. Fig. 6 is a modification of Fig. 3. Fig. 7 is a view of the top plate a, c, d or f, as in Figs. 5 or 6. Fig. 8 is a vertical central cross section of a modification of the invention. Fig. 9 is a sectional view of another modification. Fig. 10 is an enlargement of a portion of Fig. 9. Fig. 11 is a section of Fig. 14 on line A' and B'. Fig. 12 is a bottom view of Fig. 9. Fig. 13 is a bottom view of modified securing means. Fig. 14 is a sectional view of Fig. 13.

The apparatus is preferably constructed of sheet copper, or any suitable metal, and mainly comprises water containers or water heater units. Each such unit is actually a liquid heating cell which may have any form allowing for the presence of a central baffle wall, the purpose of which latter is to 60 partially obstruct the incoming liquid and to force the latter to flow to the remotest portion of the unit before it can turn to the port of exit. This causes the liquid to contact with one direct heating wall throughout its course, as it travels first on one side of the baffle walls and returns through the 65 same distance on the other side.

Referring to the drawings, the same letters and numerals refer to like parts, or 70 parts serving the same purpose throughout all the accompanying drawings.

In Fig. 1 I have the main principles of my invention. The heavy dotted lines indicate the interior construction. The arrows indicate the general direction taken by the hot gases and the definite course taken by the water through the apparatus.

In Fig. 2 of the drawings, A, B, C, D, E and F serve the same purposes as in Fig. 95 1, and are the annular walls of the water heater units or cells. Also a, b, c, d, e and f are the horizontal tops of the heater units.

The annular wall A is secured to the round disk a by spinning in the upper edge 100 of A as at K, and brazing or fastening a under this edge by any means known to the trade. In the same manner are the disks b, c, d, e and f secured to their respective walls. Disks c and f are similar to disks a and d, though of different diameters. Disks b and e, however, are really parts of the partition or baffle walls within the heater units and are slightly different from the foregoing disks. The otherwise semi-cir- 105 110

cular flue to the right is here reduced and circular, counter-sunk and provided with a lid as at *x* and *y*.

Between disks *a* and *b* is fitted a flue block 5 *X'* here shown in vertical cross section, but otherwise shown in horizontal cross section in Fig. 4, where the semi-circular flue to the left is noted by Fig. 7. Returning to Fig. 2, the same flue is occupied by but not 10 noted by letter *X'*, the flue to the extreme right by *r'*, and the central circular flue accommodates vertical valve *p*. In flue block *X'* openings lead from valve *p* and also from chambers *r'* into chamber *b'* 15 through aperture *r*. This same flue block is shown in horizontal cross section in Fig. 3. Returning to Fig. 2, the blocks *X'*, *X''*, *X'''* and *X''''* are exactly alike. The lowest flue block *T* has accommodations to the 20 extreme right for receiving the end of pipe 9, and in the center for seating the lower end of valve *p*.

Surmounting the apparatus is flue block *U*. To the right it receives the end of valve 25 *h*. To the extreme left is the exhaust vent 11, terminating in oblique position. In the center of the same flue block, a collar or nut is fitted to accommodate the stem of valve *p*. A little to the right of the latter valve is the 30 externally threaded nut *N*, tapered at its lower end and projecting down into chamber *p'*. In chamber *g* is placed valve *N'*, which engages the lower tapered end of nut *N*. Valve *N'* is by virtue of its arrangement forced toward the right by screwing 35 down nut *N*, thus allowing more water to pass valve *N'*. If nut *N* is removed, the helical spring on the stem of valve *N'* will close the latter. Directly beneath nut *N* 40 is a strainer and mesh which are accessible by removing the nut, the flow of water then automatically ceasing as has been stated.

The flue block *y'* has no horizontal vents from the central or extreme right hand flues, 45 but the flue 7 to the left communicates at 7 through the external wall with the space *d* in which the block is situated. Pipe 9 extends downward and connects with pipe *i* by means of an elbow on the level of ring *R*. Pipe *i* runs obliquely down through gas burner *O* to valve *J'*. Valve *h* controls pipe *h'*, the latter connecting below with an automatic double intake valve *v'* in casting *v''*. Pipe *h''* connects valve *v'* with external water source. The combustible gas is 55 supplied to chamber *l''* in *v''* from valve *l*. Part of the gas is diverted upward into jet *l'* which is always burning.

In operation, the valves *h* and *J'* are 60 opened, permitting a flow of water through the entire apparatus. The water from *h''* will force open and retain valve *v'* against its spring, and cause gas to pass valve *v'* up into burner *O* where it will be ignited by jet *l'*.

Noting the course of the water from valve *v'*, it flows through pipe *h'* to valve *h*, and passing valve *N'* enters chamber *p'*. Thence the water proceeds through filter *M* in disk *a* into chamber *r'* where it finds lid *x* normally closed. From chamber *r'* the water flows through vent *r* into space *b'* and down between *A* and *B* to *G*. Between *G* and *h*, the water doubles upon itself and proceeds upward in space 2 until it reaches disk *b*, 75 where the water converges toward the central flue block in space *c'*, and, finding inlet *s*, arrives in chamber *a'*. From chamber *a'* the water dives down to chamber *t'* whence it takes its course in space *e'*, down space 3, 80 to annular ring *h* and up through space 4 to space *f*. Thence the water again converges toward the center, and finding a vent *u*, enters chamber *u'*. If there were a whole series of such water heater units the water 85 would proceed through the succeeding units and make the same kind of journey through each as has just been described concerning two such units. In this case, however, the water now leaves chamber *u'*, flows down 90 through pipe 9 and out through valve *J'* to external use.

Were the apparatus to be used as a steam generator, the steam would rise simultaneously in all vertical spaces in the heater and 95 seek a general outlet. In order to meet these new conditions, the valve *p* is provided. Being turned half a revolution to the right, this valve is capable of connecting, by means of slot *n*, the chambers *u'* and *t'* through vents *n''* and *n'*. Also chambers *a'* and *r'* will be connected by slot *m* through apertures *m''* and *m'*. This will afford the steam the opportunity to rise to the uppermost 100 chambers and obviate immediate danger of 105 explosion. However, in order to further facilitate a more rapid and free exchange of steam and water and to permit the latter to constantly retain its general level throughout the entire apparatus, a valve *q* 110 is provided. On turning valve *q* half a revolution, it will connect spaces 1 and 2 with spaces 3 and 4 through slot *v* at *w* and *z*.

In order to increase the safety of the invention from within, small lids *x* and *y* are 115 provided, being temporary auxiliaries of the central valve in case the latter should be forgotten or used tardily.

If it be supposed that steam is generated in spaces 1, 2, 3 and 4, it will rise to the 120 horizontal spaces *b'*, *c'*, *e'* and *f'* and will rise from chamber *u'* to *t'* through slot *n*, up through flue *7'* to chamber *a'* where more steam joins it from space *c'*. Thence the steam passes upward through slot *m* to chamber *r'* and up to *p'* where the entire output of the apparatus gathers.

It is to be expected that steam will be generated in spaces 3 and 4 more rapidly than 130 in spaces 1 and 2, due to greater exposure

to heat. The water level would thus fall below that of spaces 1 and 2, but this is entirely counteracted by valve q , which, by virtue of slot v , permits the water from spaces 1 and 2 to flow into spaces 3 and 4, causing a compensating rise in these latter.

The heated gases from burner O pass upward in chamber 6 where they find flue 8, thence passing up to vent 7 are augmented by more gases from space 5. From this point the gases pass upward to vent 11 and then out.

It is, of course, understood that the use of gas as fuel is optional, as well as automatic valves v' and N' .

In Fig. 2 is shown one method of securing the lower parts of the apparatus. Walls A and C are clamped down by ring k in the annular recess receiving it in the annular double ring R. D and F are similarly secured. Another method of accomplishing this end is illustrated in Figs. 9, 10 and 12 of the drawings.

In Figs. 9 and 12, k' is the outer clamping ring, R and R' the inner ring further shown in Fig. 10, where S' and S'' are the opposed wedges and S the securing bolt. In the same Figs. 9 and 12, k and k' are clamping rings inclosing water spaces 1 and 3, while O' is a clamping ring containing heat flues H'. All other parts are identified by similar letters as in other figures of the drawings.

Yet another method of sealing the lower extremities is illustrated in Figs. 11, 13 and 14. Here A, C, and F are exterior walls, B is a middle wall, formed at the bottom into tongues G, G. Fig. 11 is a bottom view of Fig. 14 on line A' B'. Returning to Figs. 13 and 14, R and R' are bands or rings secured by bolts S, S, S. In the lower extremities of A, C, D and F are slots Q, Q, Q, which allow rings R and R' to be drawn off downward without actually removing bolts S, S, S, but merely by loosening the same.

Having thus fully described my invention, what I claim as new and desire to obtain by Letters Patent is:

1. In a water heater or steam generator, including a water container having two substantially plane walls spaced apart, a water inlet in one of said walls and an outlet in the other, a water baffle wall within the container spaced between and parallel to the walls thereof, a union of said walls beyond the extreme edge of said baffle wall, and independent heat flues running axially through the walls of said water container, substantially as described.

2. In an apparatus as described, including water container units, the combination in each said unit of a substantially plane water deflecting wall and a pair of substantially plane walls spaced from and inclosing the same, means located at the circum-

ference or edge of the baffle wall providing for the passage of water through or beyond said edge, a water inlet in one inclosing wall and an outlet in the other wall in positions provided to locate the water baffle wall relatively between said water inlet and outlet, and independent heat flues passing axially through the walls of said water container unit and terminating on the exterior exposed surfaces of the same, as described.

3. In an apparatus as described, including a water container having two walls spaced apart and water inlet ports in one of said walls and outlet ports in the other; a water baffle wall in said water container between the inlet and outlet ports and a plurality of independent heat flues running through said water container directly through the spaced walls thereof and included water baffle wall, substantially as described.

4. In an apparatus as described, including a pair of spaced parallel walls with a pipe fitted to each in the central portion thereof and a wall or junction uniting said walls at their peripheries; a water baffle wall spaced between said parallel walls, the edge of the baffle wall being spaced from and within the peripheral junction, independent heat flues running through said parallel walls and included baffle wall, substantially as described.

5. In the exterior water circuit of an apparatus as described, a valve containing a valve piston retained against a helical spring mounted on the shank of said piston in open position by obstructive contact of the butt of said shank with an inward projection of a threaded cap fitted in said valve in a position directly above a strainer located within said valve, said strainer being accessible and said valve simultaneously closable upon removal of said threaded cap, substantially as described.

6. In an apparatus as described, including a plurality of spaced water containers provided with water baffle walls; a series of flue blocks arranged interiorly and exteriorly of said water containers to provide one block between each pair of adjacent surfaces, heat flues running through the extent of said series and all interposed surfaces and communicating with the spaces between each adjacent pair of water containers through side apertures in the blocks located in said spaces, also independent water channels running through said flue block series and all interposed surfaces except the water baffle walls and communicating with the water spaces within the water containers through side apertures in blocks located in said water spaces, the uppermost block of said series surmounting the apparatus being fitted with pipes to the water channels in said block leaving open the heat flues there-

in, the lowest block of said series being secured beneath the lowest water container and provided with pipes to the water channels in said block leaving open the heat 5 flues therein, bolts running clear through the entire said series of flue blocks including the two extreme blocks and all interposed surfaces to secure all said parts in combination, substantially as described.

10 7. In an apparatus as described, including water baffle walls within the same, a plurality of connected water container units spaced apart and connected by means of pipes or flue blocks and arranged in vertical 15 diminishing and descending series, substantially as described.

8. In an apparatus as described, including a plurality of spaced water containers, means providing controlled connection between said water containers through their lower extreme or edge portions, said means comprising pipes individually controlled by valves, substantially as described.

9. In an apparatus as described, including 25 a plurality of spaced water containers provided with water baffle walls as described, a valve casing secured to the lower extreme or edge portions of said water containers and communicating with said containers 30 through apertures, a valve cylinder being fitted in said valve casing containing slots to provide connection between said apertures and rotatable to bring said slots into or out of proximity to said apertures, and 35 means providing temporary connection between the spaces separated by the water baffle walls within said water containers, said means comprising easily raised lids movably secured in apertures located in the 40 horizontal portions of the water baffle walls, as described.

10. In an apparatus as described, including 45 a series of flue blocks in combination with water containers, a valve seating extending throughout said series of flue blocks with apertures opening into said seating from the water channels in all blocks located within water containers, a valve cylinder fitting into said seating and containing slots 50 to provide connection between said water channel apertures, and being rotatable to bring said slots into or out of proximity to said apertures, as described.

11. In an apparatus as described, including 55 a plurality of water container units provided with interior water baffle walls; the provision of said water containers in the

form of a concentric series of spaced hollow cylinders with closed tops continuous with the individual walls of said cylinders, said 60 series inclosing a cylindrical heat chamber open below, a downward extension of the exterior surface of the outermost water container providing housing for heating means and an extension above providing a dome 65 and chimney, substantially as described.

12. In an apparatus as described, including a series of cylindrical, concentric and similar water containers inclosing a central chamber open below; the disposition of a 70 water baffle wall relatively intermediate of the walls of each said water container parallel therewith and following in spaced fashion the form of the walls inclosing the same, the lower extremity thereof being 75 spaced within and above the lower termination of the exterior walls and means providing removable lower junctions of said exterior walls and detachable means for spacing apart adjacent pairs of said walls, 80 substantially as described.

13. In an apparatus as described, including a plurality of water container units of hollow, cylindrical form, the arrangement of said container units in a diminished concentric series with the lower annular extremities thereof registering with one another, a shoulder formation toward each other of the pair of said lower extremities in each container unit, providing an annular junction of said extremities by contact, said junction being substantially parallel to the upper annular portions of the container unit walls, an annular ring exteriorly fitting each said junction, another ring fitting the inner 95 exterior surface of each said junction, a plurality of bolts running radially through said rings and included junctions securing the same, a plurality of long, radially disposed bolts running through the entire series of annular rings and junctions spacing the adjacent junctions apart and securing the whole series, and slots in the lower edges of the water container walls opening downward from all said securing bolts, permitting all rings and bolts to drop off upon loosening said bolts, as described.

Signed at New York in the county of New York and State of New York this second day of April A. D. 1915.
